UNITED STATES PATENT OFFICE.

ARTHUR J. MOXHAM, OF JOHNSTOWN, PENNSYLVANIA.

MACHINE FOR BENDING FLANGED METAL BARS.

SPECIFICATION forming part of Letters Patent No. 530,196, dated December 4, 1894.

Application filed March 23, 1894. Serial No. 504,893. (No model.)

To all whom it may concern:

Be it known that I, ARTHUR J. MOXHAM, a subject of the Queen of Great Britain, residing at Johnstown, county of Cambria, State 5 of Pennsylvania, have invented a new and useful Improvement in Machines for Bending Flanged Metal Bars, of which the following specification is a true and exact description, due reference being had to the accompanying 10 drawings.

My invention specially relates to a machine for bending that class of beams known as channel-beams, and which are composed of a web member having on each edge a flange 15 angularly disposed to the web.

The object of my invention is to provide a machine adapted to effect a short, sharp bend in a channel, as hereinafter set forth.

In bending channels it is sometimes desirable to bend them by folding together a portion of the flanges while bending the web, and it is to effect a bend of this character that my machine is adapted.

Referring to the drawings: Figure 1 is an end 25 view of a channel of the type described. Fig. 2 is a side view of the same, the dotted lines showing it after being bent. Fig. 3 is a perspective view of a channel after being bent in my machine. The fold in the flange shows 30 clearly in this view. Fig. 4 is a top view of the lower die of my machine. Fig. 5 is a front and Fig. 6, a side view of the machine.

A is a die or former, the top of which is beveled off at the proper angle to form the 35 desired angle in the channel, and which is formed to fit inside the channel when bent.

B is a mating die adapted to fit outside the channel when bent, and operated by any suitable power attached to rod O, the channel 40 being thus pressed into shape between the two dies. The movable die B is guided by any suitable guides, as the rods C on which slide the lugs D. In each side of the lower die is a pocket E, the use of which will be 45 hereinafter explained. Opposite these pockets are the fingers F so pivoted at G in block H that they may enter the pockets E and be normally held away therefrom by the springs L. These blocks H are mounted in suitable guides 50 so that they may be slid downward therein. This would compress the spring I which acts to restore the block to its normal position.

In the top die B are inclined slots K which engage the fingers F, and, as the dies come together, these inclines force the fingers inward into pockets E. 55

The operation of the machine is as follows: The channel being heated and placed in the machine, as shown, the top die descends and the edges M M striking it commence to bend it 60 over the apex of the die A. At the same time the inclines K engage the fingers F and force them inward against the flanges of the channel (see Fig. 5), and, as the die descends, the fingers continue to force the flanges into the 65 pockets E, thus making the fold shown in Fig. 3. As the fingers, though made as thin as possible, are in the folds of the flange the sides of the fold cannot come close together. Hence it becomes necessary to withdraw the 70 fingers. To do this I provide on the fingers the lugs N which engage the top die before it is fully down, and, as it descends farther, they are forced down against springs I and withdrawn from the fold in the flange. As 75 they are withdrawn from the fold before the die is fully down and while the channel is still not fully bent, the final bend in the channel closes the two sides of the fold together and thus forms the neat and compact 80 bend shown in Fig. 3.

The connection O may be joined to any suitable power, and the die B may be caused to travel in any path which will effect the bending; for instance, it may be connected 85 with a piston rod reciprocating in a straight line, or it may be attached to an arm pivoted at the other end and so engage the bar with a swinging action. It might be desired also to have both dies movable which could be 90 readily done by connecting both directly with suitable power.

The method of performing such bending as herein described, I have described and claimed in an application filed by me March 95 23, 1894, and bearing Serial No. 504,892.

Having thus fully described my invention, what I claim, and desire to protect by Letters Patent, is—

1. A machine for bending flanged metal 100 bars, consisting of a pair of dies between which the bar is bent, operating mechanism connected therewith and finger bars pivotally mounted in one die and operated by the other

die, in such manner that they are adapted to engage the flanges of the bar and bend them in the manner set forth.

2. In a machine for bending flanged metal bars, in combination with a pair of dies between which the bar is bent, and operating mechanism therefor; finger bars adapted to engage and bend or fold, as described, flanges of the bar, said finger bars being so mounted 10 that they may be withdrawn from the fold for the purpose set forth.

3. In a machine for bending flanged metal bars, in combination with a pair of dies between which the bar is bent, and operating 15 mechanism connected therewith; pockets in one die adapted to receive flanges of the bar when bent; finger bars adapted to bend or fold said flanges into said pockets; and blocks in which the finger bars are pivoted, said

blocks being so mounted on one of the dies 20 that the finger bars may be withdrawn from the folds in the flanges before the bar is fully bent.

4. In a machine for bending flanged metal bars, in combination with a pair of dies 25 between which the bar is bent, and operating mechanism; pockets in one die and finger bars normally out of said pockets, the finger bars being so connected and arranged that they are adapted to have a movement inward into 30 said pockets and downward in said pockets.

In testimony whereof I have affixed my signature in presence of two witnesses.

ARTHUR J. MOXHAM.
